(57) **CLAIM**

The ornamental design for a radar device, as shown and described.

DESCRIPTION

FIG. 1 is a front perspective view of a first embodiment of a radar device;

FIG. 2 is a rear perspective view of the radar device of FIG. 1;

FIG. 3 is a top view of the radar device of FIG. 1;

FIG. 4 is a bottom view of the radar device of FIG. 1;

FIG. 5 is a left side elevational view of the radar device of FIG. 1;

FIG. 6 is a right side elevational view of the radar device of FIG. 1;

FIG. 7 is a front elevational view of the radar device of FIG. 1;

FIG. 8 is a rear elevational view of the radar device of FIG. 1; and

FIG. 9 is a rear elevational view of the radar device of FIG. 1 shown in a configuration of use;

FIG. 10 is a front perspective view of a second embodiment of a radar device;

FIG. 11 is a rear perspective view of the radar device of FIG. 10;

FIG. 12 is a top view of the radar device of FIG. 10;

FIG. 13 is a bottom view of the radar device of FIG. 10;

FIG. 14 is a left side elevational view of the radar device of FIG. 10;

FIG. 15 is a right side elevational view of the radar device of FIG. 10;

FIG. 16 is a front elevational view of the radar device of FIG. 10;

FIG. 17 is a rear elevational view of the radar device of FIG. 10; and,

FIG. 18 is a rear elevational view of the radar device of FIG. 10 shown in a configuration of use.

(Continued)

The broken lines in the drawings are for the purpose of illustrating portions of the radar device that form no part of the claimed design.
